UNITED STATES PATENT OFFICE.

OTTO CULLMAN, OF CHICAGO, ILLINOIS.

HOLDER FOR PHONOGRAPHIC DISK RECORDS.

1,327,949.

Specification of Letters Patent.

Patented Jan. 13, 1920.

Application filed April 7, 1919. Serial No. 288,218.

To all whom it may concern:

Be it known that I, OTTO CULLMAN, a citizen of the United States, and a resident of Chicago, in the county of Cook and State of Illinois, have invented certain new and useful Improvements in Holders for Phonographic Disk Records, of which the following, when taken in connection with the drawings accompanying and forming a part 10 hereof, is a specification.

This invention relates to a holder which may be placed in a cabinet, on a table, stand or other article, and in which a plurality of phonographic disk records may be stored, 15 and from which any desired record may be easily obtained; and as readily returned thereto.

Among the objects of this invention are to obtain a holder of the kind to which it 20 relates which is economically made, is durable, not liable to get out of order, the operation whereof is easily understood, and in which a large number of records may be stored.

25 In the drawings, Figure 1 is a perspective of a frame and a lever, a plurality of said levers being utilized in a completed apparatus.

Fig. 2 is a front elevation of the holder, 30 some of the duplicate members being removed.

Fig. 3 is a side elevation, with some of the parts thereof broken away.

Fig. 4 is a top plan view, looking down.

35 Fig. 5 is a side elevation of a partition forming an element of the apparatus.

Fig. 6 is a perspective of one corner of a plurality of partition members, and of the separating member holding them in spaced 40 relation.

And Fig. 7 is a side elevation of a supporting rod, a spring and a nut positioned on said rod, an edge elevation of a partition member, and a vertical section of a lever 45 element.

A reference character applied to designate a given part indicates said part throughout the several figures of the drawings wherever the same appears.

50 The frame of the holder comprises the base A, standards B, bars C, and cross bar D. Bars C are illustrated as respectively provided with notches or recesses E. F, F, represent rods which extend transversely from one bar C to the other one thereof, and said rods are held in a predetermined

position on said bars C, C, by the ends thereof being in the recesses or notches E, E. G, G, represent partitions which are supported by rods F, F, and held in spaced 60 relation by the bars H, H. Partitions G are provided with apertures through which the rods F, F, extend, said apertures being designated by the characters J, J, and the partitions are reinforced around and adjacent to said apertures by the eyelets I, I.

F¹, represents an additional rod which extends through apertures J¹ in partitions G; and I¹ represents an additional eyelet which reinforces said partitions around and adjacent to said apertures J¹. K, K, represent levers which are pivotally mounted on rod F¹, between partitions G, G. In Fig. 1 a lever K is illustrated which is curved, and in Fig. 3 a similar lever is illustrated which is not curved. By using the curved lever which is illustrated in Fig. 1 the rod F¹ may be nearer the base A than where the straight lever illustrated in Fig. 3, is used; but as the function of said levers is the 80 same, whether a curved or a straight one is used I do not consider one a modification of the other. k represents a step on the operable end of lever K. Step k is to permit a pencil or stylus to be used to force said 85 end down when a disk is to be obtained from the holder. L, (Fig. 7) represents a space between adjacent partitions G, G, and said space constitutes a receptacle in which a disk (X), may be stored, with the edge 90 thereof resting on lever K, as is illustrated in Fig. 3. The several levers K, K, between the partitions G, G, are held in close relation (by spring M and nut N, which are mounted on the ends of said rod F¹) to said 95 partitions. The ends of rod F¹ are screw threaded and the nuts N, N, may be turned on said rod to increase the tension of spring M sufficiently to maintain a lever K in a predetermined position; that is, when the 100 end of a predetermined lever K having step k thereon, is depressed said lever will remain depressed, and when said end is raised into normal position it will remain in said normal position. Any expansion of partitions G, G, and levers K, K, is compensated for by said springs M, M.

To store a disk in said holder it is simply necessary to roll it into a space or chamber L and raise the stepped end of the lever K 110 on which said disk rests into substantially the position which is illustrated in Fig. 3.

It is immaterial whether the stepped end of said lever K is depressed or raised at the time the disk is placed thereon and rolled into the space or chamber L, but to retain 5 said disk in said space the end of said lever is raised. To release a predetermined disk from the holder the stepped end of the lever K which is supporting said disk is depressed sufficiently to cause said disk to roll on said 10 lever into grasping position. Having depressed the stepped end of a lever K and taken the disk which rests thereon therefrom, said end will remain in said depressed position; and by so leaving it the space or 15 chamber to which said disk should be returned is indicated. Upon the return of said disk to said space or chamber it will remain therein upon the raising of said stepped end of the lever on which it rests to 20 normal position.

I claim:

1. In a holder for phonographic disk records, a frame, partitions, means to hold said partitions in spaced relation and supported by said frame, in combination with levers pivotally mounted between said partitions, and means to yieldingly hold said partitions and levers in close relation.

2. In a holder for phonographic records, 30 a frame, rods extending transversely of said frame and supported thereby, partitions mounted on said rods, means to hold said partitions in spaced relation, in combination with an additional rod extended 35 through said partitions and supported thereby, and levers pivotally mounted on said additional rod and between said partitions.

3. In a holder for phonographic records, 40 a frame, rods extending transversely of said frame and supported thereby, partitions mounted on said rods, means to hold said partitions in spaced relation, in combination with an additional rod extending through

said partitions and supported thereby, levers pivotally mounted on said additional rod, 45 and means to yieldingly hold said partitions and said levers in close relation.

4. In a holder for phonographic records, a frame comprising a base, standards, bars connecting said standards, from front to 50 rear, and recesses in said bars, rods in said recesses extending transversely of said frame, partitions respectively provided with apertures mounted on said rods, with said rods extending through said apertures, separating members on said rods, between said partitions, arranged to hold said partitions in spaced relation, additional apertures in said partitions, and a rod extending through said additional apertures, levers pivotally 55 mounted on said last named rod, and means to hold said partitions and said levers in close relation, all combined as set forth.

5. In a holder for phonographic records, a frame comprising a base, and standards, 65 bars extending from the rear to the front standards, rods supported on said bars and extending transversely on said frame, partitions provided with apertures and means to reinforce said partitions around said 70 apertures, separating members on said rods to maintain said partitions in spaced relation, additional apertures and additional means to reinforce said partitions around 75 said additional apertures, in combination with a rod extending through said additional apertures, levers pivotally mounted on said last named rod, springs on said rods and means to force said springs against adjacent partitions to maintain said levers and partitions 80 yieldingly in close relation.

OTTO CULLMAN.

In the presence of—

CHARLES TURNER BROWN,
E. A. WINCHELL.
